UNITED STATES PATENT OFFICE.

DWIGHT L. WARRICK, OF YORK, NEBRASKA.

GAS GENERATOR.

Application filed July 9, 1925. Serial No. 342,464.

To all whom it may concern:

Be it known that I, DWIGHT L. WARRICK, a citizen of the United States, residing at York, in the county of York, and State of Nebraska, have invented certain new and useful Improvements in a Gas Generator, of which the following is a specification.

The present invention appertains to gas generators of that type used particularly in chemical laboratories, and similar places, for supplying gases such as hydrogen, hydrogen sulfid, or carbon dioxid, in quantities.

An important object of the invention is the provision of a generator of this character which will generate either large or smaller quantities of gas as rapidly as the gas is used, and which will be entirely automatic in its operation, that is, it will supply acid to the solid reagent with sufficient rapidity to generate gas as fast as it is required and will automatically shut off the flow of acid as the demand for gas diminishes or entirely ceases.

Another very important object of the invention is to provide an automatic generator of this nature which will eliminate the undesirable siphoning which usually takes place in the structures now in common use in laboratories, and other similar places, between the reagent receptacle and the liquid container.

A still further object of the invention is to provide a generator of this class including a minimum number of parts having exceedingly simple structures, one which is capable of being easily assembled or disassembled, one which is thoroughly efficient and reliable in operation and otherwise well adapted to the purpose for which it is designed.

With the above and numerous other objects in view as will be better understood as the description proceeds, the invention resides in certain novel features of construction, and in the combination and arrangement of parts as will be hereinafter more fully described and claimed.

In the drawing:

The figure is an elevation of the generator apparatus embodying the features of my invention.

Referring to the drawing in detail it will be seen that 5 designates a solid reagent container wherein will be disposed different materials such as zinc for instance. This receptacle is in the form of a bottle having the open neck 6 at its upper end. The bottle

is apertured adjacent its bottom to receive a cock 7 in order that surplus fluid may be drained therefrom when desired. A neck 8 is provided to the side of the intermediate portion of the receptacle 5. A liquid container 9 is also in the form of a bottle having at its upper end a neck 10, at its intermediate portion a neck 11, and at its bottom portion a neck 13. The container 9 is on the same level with the receptacle 5. A hose or the like 14 is disposed between the two necks 8 and 11 in order that a tube 15 may terminate in the receptacle 5, and in the container 9. At the termination of the tube 15 in the container 9 it is provided, if desired, with an upstanding perforated extension 16 which is closed at its upper end. A gas take-off tube 17 is provided with branches 18 and 19 entering necks 10 and 6 respectively. A flexible tube 20 communicates with the neck 13. A liquid supply container 21 is disposed at a higher level than the receptacle 5, and container 9, and has a filling neck 22 at its upper end, and an outlet neck 23 at its lower end, the latter of which is in communication with the flexible tube 20.

The solid reagent is placed in the receptacle 5 and the liquid in the form of a suitable acid is placed in the liquid supply container 21, and will flow therefrom into the liquid container 9, and when this acid reaches the level of the tube 15 it will flow over into the receptacle 5 engaging with the solid reagent so as to generate gas in the well known manner. The gas will escape through the branch 19 and tube 17. When the gas has been shut off it will be seen that instead of flowing through the tube 17, the gas will flow through the branch 18 into the container 9 so as to cause a back up pressure in the top of this container until the level of the acid therein is below the tube 15 and thereby prevent any further generation of the gas. The construction of the tube 17 with its branches 18 and 19 in communication with the container 9 and receptacle 5 respectively through branches 18 and 19 respectively will prevent any siphoning action between the receptacle 5 and the container 9. It will also be seen that the collection of the gas in the container 9 will afford an additional supply of gas when said gas is being utilized faster than it can be normally generated by the apparatus.

It is thought that the construction, operation, utility, and advantages of my gener-

ator will now be clearly understood by those skilled in this art without a more detailed description thereof. It is desired, however, to point out that the present embodiment of the invention has been disclosed merely by way of example since in actual practice it attains the features of advantage enumerated as desirable in the statement of the invention and the above description.

10. It will be apparent that numerous changes in the details of construction, and in the combination and arrangement of parts may be resorted to without departing from the spirit or scope of the invention as herein-
15 after claimed or sacrificing any of its ad-
vantages.

Having thus described the invention, what I claim as new and desire to secure by Letters Patent is:—

20. 1. A gas generator comprising a liquid container, a reagent receptacle on the same level with the liquid container, a liquid supply container at a higher level than the liquid container, means communicating the bottom of the liquid supply container with the bottom of the liquid container, means communicating the tops of the liquid container and the reagent receptacle, a take off tube incorporated in said means, and
25 means communicating intermediate portions of the liquid container and the reagent receptacle.

30. 2. A gas generator comprising a liquid container, a reagent receptacle on the same level with the liquid container, a liquid supply container at a higher level than the liquid container, means communicating the bottom of the liquid supply container with

the bottom of the liquid container, means communicating the tops of the liquid container and the reagent receptacle, a take off tube incorporated in said means, means communicating intermediate portions of the liquid container and the reagent receptacle, said last mentioned means having an upwardly disposed apertured tubular portion within the liquid container.

3. A gas generator comprising a liquid container, a reagent receptacle on the same level with the liquid container, a liquid supply container at a higher level than the liquid container, means communicating the bottom of the liquid supply container with the bottom of the liquid container, means communicating the tops of the liquid container and the reagent receptacle, a take off tube incorporated in said means, means communicating intermediate portions of the liquid container and the reagent receptacle, and draining means associated with the bottom portion of the reagent receptacle.

4. A generator of the class described comprising a reagent receptacle, a liquid container, a liquid supply tank, said container and receptacle being on approximately the same level and said tank being on a higher level, means communicating the bottom of the tank with the bottom of the container, means communicating the intermediate portions of the receptacle and container, and a take off tube having branches engaged one with the top of the receptacle and the other with the top of the container.

In testimony whereof I affix my signature.

DWIGHT L. WARRICK.
